CANNED OIL DISPENSER

Otto Anderson, Paulsbo, Wash.

Application June 24, 1938, Serial No. 215,684

6 Claims. (Cl. 221—23)

My present invention relates to the art of dispensing devices and more particularly to a canned oil dispenser.

There is a marked insistence on the part of many motorists for lubricating oil that is packaged by its producers and sold in sealed, tin containers. In this way the consumer knows that he is getting exactly the oil specified by the maker of his car for the condition and mileage of his car. This insistent demand has made desirable a dispenser that will conveniently drain the oil from the can into the crank-case of the car. Many devices have been produced for this purpose; however, they have been characterized by certain deficiencies such as the difficulty of their operation; the fact that the dispensers themselves, in many instances, retain undispensed a certain amount of oil that is mixed with the next can of oil opened which may be of a different character. Further, the devices observed have often been difficult to operate or required that the can be punctured by a separate device and then brought out to the car and inverted into a funnel or some such arrangement. This method of operating often leads the service station operation into difficulties; particularly when a motorist may change his mind, for instance, on the exact weight of oil that he desires, or when there may have been a misunderstanding between the car owner and the station operator.

With my present dispenser I provide means which can be very easily operated by a youth, a woman, or anyone not particularly skilled in that type of operation; and one which operates with certainty, which cuts the dispensing opening and the vent opening with ease and by a single operation at the instant just before the oil is to be drained into the crank case. In some instances a third puncture is provided for in the side of the can.

The principal object therefore of my present dispenser is to provide a convenient and easily operated means for draining the contents of a container into the crank-case of a car.

A further object of my present invention is to provide a device for dispensing oil that by its very nature can be very economically constructed to the end that it may be sold cheaply, and can be expected to give long periods of satisfactory service.

Still another object of my present invention is to provide a dispenser with a spout attachment and general construction that admits of easy servicing of any of the known makes of cars.

Other and more specific objects will be apparent from the following description taken in connection with the accompanying drawings, wherein

Figure 1 is a perspective view showing a liquid dispenser made after the teachings of my present invention.

Figure 2 is a perspective view showing the dispensing, or draining, opening cutter together with the fulcrum used in the operation of my device.

Figure 3 is a perspective showing the means employed for making the vent opening and, where required, in making the body puncture for purposes of defacing the oil container.

Figure 4 is a top plan view of the dispenser of Figure 1.

Figure 5 is a side elevation of my dispenser, certain parts of which are shown in section, with a can in place ready for opening which can, itself, is shown in section.

Figure 6 illustrates, in perspective, the vent puncture produced by my device.

Figure 7 illustrates, in perspective, the dispensing, or draining, opening as formed in a tin container together with a body puncture.

Figure 8 is a view similar to Figure 5 excepting that the can is shown as opened, in its dispensing position, with the spout also shown in its dispensing position.

Referring to the drawings, throughout which like reference characters indicate like parts, 10 designates the body of my dispenser. This should be made of a size that will have sufficient capacity to accommodate the full volume of the can of liquid to be dispensed. This makes it possible to use the same without danger of over flowing as may occur if there should be any reason for stopping the dispensing after the can is opened. The dispenser is preferably formed with a tapering body, or at least a tapering upper portion so that the two positions of the can, that before it is opened and the one after it is opened, readily can be accommodated. Also conveniently arranged is a suitable handle as 12 which is normally secured to body 10 as by riveting the same thereto.

Disposed somewhat up from the bottom of body 10 is the bottom proper 14. This I prefer to form as a separate member which can be formed by pressing, or forming, and then securing it in position by some convenient means such as welding, soldering, or riveting. The principal requirement of bottom 14 is that it be so arranged as, for instance, after the showing of Figures 5 and 8, that all the oil will drain from the body of container 10 when a can of oil is being dispensed.

Then too, as a matter of convenience, so that the device will sit level when not in use, I prefer that the discharge as 16 be so arranged that it comes out through the side wall of container 10 as is 5 illustrated at 17. In this way the lower rim of the container proper will form a plane and serve as a rest for the device. Attached to outlet 16 is a section of flexible tubing 18. This is desirable first, to provide means for starting or stopping the flow of oil after the showing of Figures 5 and 8, where the two positions of the spout are clearly shown; and, secondly, to provide flexibility in the discharge spout so that inaccessible or unusual filling openings can be easily reached. Secured to the end of the flexible tubing 18 I prefer to provide a section of solid tubing 20 having at its extreme end a downwardly turned discharging spout 21. This arrangement provides for the greatest ease of operation and cleanliness in that 10 the smooth tubing 20 can easily be wiped clean, although it normally will run clean. This is not true of the usual flexible tubing as shown at 18.

The spout assembly consisting of members 18 and 20 are held in position by preferably two 25 tension springs 19; these are secured by suitable means to both the can body and the spout and, act as toggle springs; when the device is in its upper position as shown in Figure 5 these springs tend to raise it still further and when, in the 30 lowered position of the spout, as shown in Figure 8, the springs again tend to maintain the spout in its depressed position.

Secured within body 10 above the bottom 14 is the main opening cutter and fulcrum illustrated probably best in Figure 2. This consists of the opening member proper 22, which is provided with a down-turned portion as at 24 and another down-turned portion at 26. These form a means for attaching the cutter to the body 40 10. This attachment may again be by any convenient means, in the drawings I have illustrated riveting, although it will be apparent that soldering, brazing, or welding might be employed. The support member 26 is formed by striking the same 45 out of the center of member 22 so as to provide an opening at 27.

Secured also to member 22 is a rest or fulcrum member 30; this I prefer to form with an upturned edge at 31 to form the actual fulcrum, 50 two down-turned portions 32 and 33 which provide means for attaching the same to the body 10.

Secured to body 10 preferably by the same means that secures leg 24 of member 22, is the venting member 35. This member consists essentially of a resilient, preferably spring stock strap 36 which is secured to body 10 and has at its upper end the venting point 38. This point is further provided, preferably, with a groove as at 39 so as to with certainty provide a free passage for the entry of air into the can as the oil is being dispensed. It has often been found that there is a requirement that the can body itself be mutilated so that the can cannot again be used. To provide this puncture I have shown 60 an auxiliary point at 40 which will puncture the can in its body portion.

Method of operation

In using my dispenser the first operation is to 70 place the tin can in the container body after the showing of Figure 5. When so placed the lip or rim 43 of the can 42 is so placed as to engage lug 44 formed as part of member 22. The can is tilted naturally to the left as viewed in Figure 75 3 by virtue of its resting on point 28. In this

position member 36 is displaced to the left as shown in Figure 5 with point 38 above but not engaged in the top of the can. With the can so placed the next operation is to take the dispenser and the can to the point where the liquid or oil is to be used. The spout assembly is now depressed against the tension of springs 19 until they pass their center of action and then tend to pull the spout still lower as is shown in Figure 8, and spout 21 is entered in the filling opening. The operator then moves the top of the can to the right as viewed until it assumes the position shown in Figure 8. Here it will be observed point 28 has entered far into the bottom of the can providing the discharge or dispensing opening 46; at the same time point 38 has pierced the top of the can at 43 and air is free to flow in through groove 39; also if the device is provided with the mutilating point 40 it will have pierced the body of the can, as at 50.

In order to bring about sufficient displacement of can 42 so as to bring point 38 well into the cover, it is necessary that the can proper be rocked as about fulcrum 31 so, in effect, that portion of the rim of the can shown to the left as viewed in Figures 5 and 8 will be raised against the point 38. During this rocking operation, of course, the desirability of having member 36 flexible will be apparent so that, without special attention from the operator, it will follow the can as it is rocked or as its top is pushed to the right in the opening operation.

It will now be apparent it is believed that a reasonably large opening will be provided in the bottom of the can at 46 and that the vent opening 48 will be provided in the top of the can admitting air to prevent the oil becoming air bound, or trapped, in the can. Further, it will be noted that the bottom opening is so made that the oil can fully drain out inasmuch as the final position of can 42 leaves the can in an angularly disposed position permitting an assurance that all the liquid will drain from it through the device.

Throughout my description I have discussed my device as being used for that purpose which, at present, appears to be the one most desirable for such an arrangement. However, it is believed it will be apparent that my device could be suitably made for use under any condition where it is desired to open and drain a sealed container made of sheet metal, paper, or other sheet products. By suitable design my device could be used with cans of square or rectangular section just as easily as with the round, and it might be used to drain fruit juices, or any other liquid from containers just as effectively as it is used for the draining of oil.

This dispenser could also be used as a measuring unit by marking on body 10 the height of the volume of liquid to be dispensed.

The foregoing description and the accompanying drawings are believed to clearly disclose the preferred embodiment of my invention but it will be understood that this disclosure is merely illustrative and that such changes in the invention may be made as are fairly within the scope and spirit of the following claims:

Having thus fully described my invention, what I claim as new and desire to secure by Letters Patent is:

1. In a liquid-dispenser in which a can is adapted to be bodily confined and rocked for opening, the combination of means depressed substantially within the dispenser for supporting the can in tiltable position, and can-puncturing

means mounted on the supporting means within the dispenser in position to cut a pouring-hole in a head of the can when the latter is rocked under pressure into contact with the can-puncturing means.

- 5 2. In a liquid-dispenser in which a can is adapted to be rocked under hand-pressure for puncturing a pouring-hole and a venting-hole, the combination with an interior support upon 10 which the can rests in rockable position, and puncturing-means mounted on the support in position to puncture a hole in the lower head of the can, of a flexible support mounted on the dispenser in axial alinement with said puncturing 15 means, and a vent-cutter mounted on the flexible support adapted to form a vent-opening in the upper head of the can, said puncturing means and vent-cutter being operable under a single rocking movement of the can.
- 20 3. In a liquid dispenser in which a can is adapted to be rocked under hand-pressure for puncturing holes in its opposite heads, the combination with an interior support on which the can rests in rockable position, and an upwardly projecting cutter mounted on the support in the path of movement of the lower head of the can, of a flexible support mounted on the dispenser in axial alinement with said cutter, and a downwardly projecting cutter mounted at the free end 25 of said flexible support in the path of movement of the upper head of the can.

4. In a liquid dispenser having an upwardly and outwardly flaring top portion in which a can is adapted to be rocked under hand-pressure, the combination with an interior rest, a transversely extending fulcrum, and an upwardly extending cutter, of a resilient support mounted at the front of the dispenser, and a downwardly projecting cutter mounted at the free end of the resilient support, whereby a pouring-hole and a vent-hole are cut in the respective heads of the can when 10 the latter is rocked on the fulcrum.

5. In a liquid dispenser in which a can is adapted to be bodily confined and rocked for opening, the combination with a fixed interior support substantially depressed within the dispenser and forming a fulcrum for the can, of a spaced cutter rigid with the support and projecting upwardly therefrom to initially support the can before it is rocked to puncturing position of the cutter.

6. In a liquid dispenser in which a can is adapted to be rocked for puncturing, the combination with an interior substantially depressed support having an upper fulcrum edge partially supporting the can in rockable position, of an upwardly projecting cutter spaced from the fulcrum edge and mounted on the support, and said cutter forming an initial support for part of the can before the latter is rocked upon the fulcrum edge.

30 OTTO ANDERSON.
